HYDRAULIC PLASTIC-EXTRUDING MACHINE WITH AUTOMATIC CUT-OFF

Application filed November 7, 1927. Serial No. 231,557.

Our present invention being referred to as an hydraulic extruding machine with automatic cut-off, it may be understood to be an object of this invention to form, from clay or another plastic material, hollow or other cylindrical or prismatic bodies such as ordinary or special tile; and our invention relates more particularly to (1) means facilitating control of the intermittent advance of a ram, 10 (2) to the construction of a "mud cylinder" and feed hopper (3) to a construction, for use with said cylinder, permitting a continuous feed of clay, or the like, to said cylinder; and (4) to means rendering the advance 15 of a so-called scale rod, or the like, effective automatically to discontinue, after a predetermined movement, the advance of said ram within said cylinder.

Other objects of our invention, including 20 a preferred arrangement of connections between a constantly-operating pump and a supply tank and between said pump and the interior of said ram, and including also means permitting either a manual or an automatic initiation of each advance of said ram, and including also means favorable to a retardation or to an acceleration of a movement of said scale rod, or its equivalent, may be best appreciated from the following description of an illustrative embodiment of 25 our invention, taken in connection with the appended claims and the accompanying drawings, in which

Fig. 1 is a somewhat diagrammatic elevational view, with parts broken away, showing the essentials of an organization embodying our invention.

Fig. 2 is a detail view corresponding to an upper right central portion of Fig. 1, but showing a ram or plunger as sectioned in a median plane.

Fig. 3 is a detail view showing one suitable type of manually oscillable valve, for use in an organization of the general character illustrated in Fig. 1.

Referring to the details of that specific embodiment of our invention chosen for purposes of illustration, uprights 11 and beams such as are shown at 12, 12' and 13 being respectively vertical and horizontal elements

of a main frame supported by foundations 14, we show a cylinder 15, for the reception of a suitable clay or other plastic material, as supported, by said frame, beneath a movable ram or plunger 16 and above a receiving plate 17, upon the upper end of a so-called scale rod 18,—the latter being shown as extending through a floor 19 and a guide 20 and as provided with not only an automatic returning means (comprising variable weights 21) but also with a tappet or adjustable stop member 22 (provided for a purpose which we will hereinafter describe).

Upon the mentioned frame or the floor 19, we may install a pump 23 (which may comprise a continuously-driven rotor whose efficiency depends upon the manipulation of interior parts by means such as a link or valve rod 24—the details of this pump, which may be of the Hele-Shaw type, being of minor importance to our present invention); and we show a tank 25 as connected therewith not only by a valved pump-supply pipe 26 (which may contain a check valve V) but by a valved branch 27, communicating with an outlet fitting 28—through which water or other fluid may be constantly or intermittently forced by said pump.

An oscillable valve 29 being interposed in the return pipe 27 and being shiftable by means such as a link or rod 30, both this link and the mentioned link 24 may be connected to a lever 31. This lever 31 is shown as pivoted at 32 and as provided with a handle 33, which may be capable of effecting either a synchronous or a separate control of the action of pump 23 and valve 29.

For example, a shifting of the lever 31 to a position such as that illustrated in full lines in Fig. 1, may simultaneously render the pump 23 efficient and shift an interior valve element of the general character illustrated at 34, Fig. 3, to a closed position, thereby compelling the pumped water or other liquid to advance through a pipe 35, communicating with a so-called fixed or interior ram element 36,—to advance the outer or movable ram element 16, forcing the same into the cylinder 15, or its equivalent.

We show the mentioned valve element 34

of valve 29 as connected (by a shaft 37, extending through a gland 38) with a lever 39 to which the link or rod 30 is pivotally connected at 40; we show the interior or fixed ram element 36 as surrounded by a gland 41, and we also show a fixed head 42, by which the inner ram inlet 36 is supported from the horizontal element 12' of the described main frame, as provided with a gland 43,—surrounding a nipple 35' by which the pipe 35 communicates with the interior of said fixed ram element; but the expedients just above referred to may be regarded as merely standard practice in the adaptation of machine parts, of the indicated general character to hydraulic operation,—in which a so-called accumulator might obviously replace the described tank.

Similarly, we allege no patentable novelty in our use of means such as restorative counter-weights 44, 44', shown as connected with a flange or lugs 45 upon the ram 16 by means of flexible tension element 46, extending over pulleys 47,—limit stops or fixed rests 48 being preferably provided beneath the restorative weights 44, 44'; but we attach considerable importance not only to the smooth cylindrical form of the exterior of the disclosed movable ram or plunger (as obviating any appreciable tendency to lift the clay or other plastic material during the rise or retractive movement of said plunger) and we attach importance also to the provision of a hopper 49, of such capacity, shape and elevation, relatively to said plunger and said cylinder, that tempered clay, or another plastic material may be continuously delivered thereto, (as, by means of a conveyor 50) during both downward and upward (or inward and outward) movements of said plunger,—the withdrawal of the same to an elevation such as that in which it is illustrated being effective to permit the descent of any accumulation of said plastic material into cylinder 15, in readiness for a repetition of extruding operations interrupted by suitable manipulations of the lever 31 or its equivalent.

We come now to what may be regarded as the most outstanding features of novelty in our present invention,—these features being favored by the employment of the described hydraulic means of control. Such control permits the movable ram or plunger 16 to be promptly stopped,—in a manner which is not practicable in case steam or another expansible fluid is employed in advancing a ram or plunger. A cross head 51 being secured on the lower end of said scale rod 18 and connected with weights 21 by means such as flexible tension elements 52, extending over drums 53 upon a shaft 54, we show a lever 55 pivoted at 56 upon a bracket 57. This bracket may be attached to a subsidiary frame 58 which provides bearings 59, 59' for the shaft 54; and we show the lever 55

as connected by a rod or link 60 with a downward extension or arm 61 of the mentioned lever 31.

A roller or other terminal member 62 may be so positioned and secured upon an arm 63 of the lever 55 as to be engaged by the adjustable tappet or stop arm 22 upon the scale rod 18, or its equivalent, whenever this rod (forced downward against the tendency of weights 21, by the extrusion of a formed product upon the receiving plate 17) has descended through a predetermined distance,—obviously dependent upon the adjustment of stop 22, or its equivalent, in accordance with the preferred length of the extruded tile or other product; and it will be obvious that, after an inward movement of the rod or link 60, in the direction indicated by the arrow 64 (a spring 65 being preferably secured upon an extension 66 of said rod or link) to manipulate the valve rod 24 and stop the pumping of pump 23, a manual or other shifting of the lever 31 (as, a shifting thereof from the dotted line position into which it may be drawn by engagement of the tappet 22 with the roller 62, or its equivalent, to the position in which said lever is shown in full lines) may be relied upon to initiate another advance of the plunger 16, after a formed article has been manually or otherwise removed from the receiving plate 17, or its equivalent,—said plate having then been permitted to return to an upper or inner position such as that in which it is shown in full lines in Figs. 1 and 2.

It will be obvious that a step-by-step or interrupted advance of the plunger 16 may be effected by merely repeatedly reducing the efficiency of the pump 23 practically to zero, without opening the valve 29, or its equivalent; but the return of the said plunger to its elevated or retracted position, under the action of counterweights 44 or 44', to permit the admission of a new charge of clay or other plastic material from the hopper 49 through an annular passage 67, or its equivalent, may be dependent upon an opening of this valve, or its equivalent,—as by shifting the lever 31 to an extreme position such as that indicated by the showing of its handle at 33', Fig. 1.

On the other hand, the cooperating parts may be so proportioned, if desired, that the tappet or stop member 22 is effective simultaneously or sequentially to render the pump 23 inefficient and to open the valve 29, or its equivalent.

We show the rod 60 as provided not only with the snap-action spring 66, which may be comparatively heavy, but also with a so-called safety spring 68, which may be comparatively light, but nevertheless adequate to restore the arm 63, or its equivalent, from a position such as that in which it is shown in dotted lines to its full line position; any

requisite means (for example a post 69, shown as resting upon a separate pier 70 and as slidably interfitting within the scale rod 18) may be employed to provide guidance therefor, during the mentioned advances and/or reciprocations; and, in order to control the rate of movement of said scale rod, especially in its automatic return movements under the action of the counter-weights 21, we may employ retarding means such as a brake 71, movable by means such as a pedal 72, and/or accelerating means such as hand wheel 73. The latter is shown as connected with a shaft 74 extending through a post 75 and terminating in a bevel gear 76, adapted to engage a co-operating gear 77 upon the shaft 54,—which may be held in its intended relationship to the shaft 74 by means such as additional brackets or hangers 78 and/or 79.

The general mode of operation of our hydraulic extruding machine having been fully indicated in connection with the description of the respective parts thereof, (omitting mention of various auxiliary devices which are immaterial to this invention) we call especial attention to the fact that each shifting of the lever 31 to a position such as that in which it is shown in full lines, in Fig. 1, may be effective, by closing the valve 29 and rendering the pump 23 efficient, to cause a downward or other advance of the plunger 16, or its equivalent, the extrusion of the formed product unto the receiving plate 17 being effective to produce a corresponding advance of the scale rod 18 until, an article of the desired length being then formed, the tappet or stop arm 22 engages the roller 62. This may so shift the lever 31 that its handle occupies the position 33",—the pump 23 being then rendered inefficient while the formed article is removed from the receiving plate 27 (manually or by any suitable means not shown) and while said receiving plate is automatically or otherwise returned to its position of engagement with an apertured forming head 80 at the lower or outer end of the cylinder 15 or its equivalent. A further advance of the ram or plunger 16 may then be effected by a restoration of the lever 31, or its equivalent, to a position such as that in which it is shown in full lines (this restoration being effected either manually, or by automatic means such as a chain or other flexible tension element 81, optionally interconnecting the receiving plate 17, or its equivalent, and the arm 63, or its equivalent); but, after the plunger 16 has been advanced approximately to its limit, a manual or other shifting of the lever 31 to a position such as that suggested by the showing of its handle at 31' may be effective not only to render the pump 23 inefficient but to open the valve 29 in such a manner as to permit a retraction of said plunger, under the action of the counter-weights 44, 44' or other restorative means; and the plastic ma-

terial continuously or otherwise fed into the hopper 49, or its equivalent, may then automatically refill the cylinder 15, or its equivalent, in readiness for a repetition of the described operations.

The provision of means such as the brake 71 (for a retardative effect) and the hand wheel 73 (usually employed for an accelerative effect, in case of sticking), being standard practice, it will be understood that these features are shown only for the sake of completeness—no claims being directed separately to means for control of the upward or restorative movement of the scale rod 18; but it should be noted that the actions of the springs 65 and 68 are such as to permit the upward or inward advance of the stop 22 past the roller 62,—although the said stop need never pass said roller, or its equivalent, in case these elements are suitably shaped and positioned.

I claim as my invention:

1. In a machine for the formation of plastic products by extrusion: a cylinder, for the reception of plastic material, provided with a forming head; a receiving plate reciprocably supported by means comprising a scale rod therebelow; a ram movable by hydraulic means, in said cylinder; hydraulic means, comprising a pump, communicating with a pipe having a valved branch for imparting movement to said ram; and means, comprising a member or members movable with said scale rod, and parts movable thereby, for interrupting the movement-imparting action of said pump, upon the extrusion of an article of predetermined length,—said last mentioned means comprising means for varying the efficiency of said pump.

2. In a machine for the formation of plastic products by extrusion: a cylinder, for the reception of plastic material, provided with a forming head; means for expressing said material through said forming head; movable means for receiving a formed product; and means, automatically actuated upon the advance of said movable means through a predetermined distance, for interrupting the action of said expressing means.

3. In a machine for the formation of plastic products by extrusion: a cylinder, for the reception of plastic material, provided with a forming head; means for expressing said material through said forming head; movable means for receiving a formed product; and means, automatically actuated upon the advance of said movable means through a predetermined distance, for interrupting the action of said expressing means,—said interrupting means comprising a member mounted on a rod by which said movable means is supported, and parts movable thereby.

4. In a machine for the formation of plastic products by extrusion: a cylinder, for the reception of plastic material, provided with a forming head; means for expressing

said material through said forming head; movable means supported by a scale rod for receiving a formed product; and means, automatically actuated upon the advance of said movable means through a predetermined distance, for interrupting the action of said expressing means,—said expressing means being hydraulically operated by a power fluid, and said interrupting means comprising a member on said scale rod by which said movable means is supported, and parts movable thereby to vary the flow of said power fluid.

5. In a machine for the formation of plastic products by extrusion: a cylinder, for the reception of plastic material, provided with a forming head; a receiving plate movably supported by means comprising a scale rod therebelow; a ram movable, by hydraulic means, in said cylinder; hydraulic means, comprising a pump, for imparting movement to said ram; and means, comprising a member on said scale rod and parts movable thereby, for interrupting the movement-imparting action of said pump, upon the extrusion of an article of predetermined length.

6. In a machine for the formation of plastic products by extrusion: a cylinder, for the reception of plastic material, provided with a forming head; a receiving plate reciprocably supported by means comprising a scale rod therebelow; a ram, movable by hydraulic means, in said cylinder; hydraulic means, comprising a pump communicating with a pipe having a valved branch, for imparting movement to said ram; and means, comprising a member movable in accordance with movements of scale rod and parts movable thereby, for interrupting the movement-imparting action of said pump, upon the extrusion of an article of predetermined length,—said last mentioned means comprising a connection to the valve in said valved branch.

7. An organization of the general character defined in claim 6 in which said interrupting means comprises also a lever, capable of hand manipulation, which is provided with means for varying the efficiency of said pump.

8. An organization of the general character defined in claim 6 in which means are provided whereby a restorative movement of said scale rod is automatically effective to initiate a further advance of said ram.

9. An organization of the general character defined in claim 6 in which means are provided whereby a restorative movement of said scale rod is automatically effective to initiate a further advance of said ram, subject to control by a hand lever.

10. An organization of the general character defined in claim 6 in which said last mentioned means comprise also a hand lever;

and in which means are provided whereby a restorative movement of said scale rod is subject to retardation or acceleration by means which are conveniently disposed with reference to said lever.

11. In a machine for the formation of articles by extrusion, a cylinder for the reception of plastic material provided with a forming head, said cylinder being of sufficient capacity to hold a charge of material sufficient for a plurality of the desired articles, means for expressing said material through said forming head, movable means for receiving a formed product, and means automatically actuated upon the advance of said movable means through a predetermined distance for interrupting the action of said expressing means.

12. In a machine for the formation of articles by extrusion, a cylinder for the reception of plastic material provided with a forming head, said cylinder being of a capacity to hold a charge of said material sufficient for a plurality of the desired articles, means for expressing said material through said forming head, movable means for receiving a formed product, and means automatically actuated upon the advance of said movable means through a predetermined distance for interrupting the action of said expressing means, said interrupting means comprising a member mounted on a rod by which said movable means is supported, and parts movable thereby.

13. In a machine for the formation of articles by extrusion, a cylinder for the reception of plastic material provided with a forming head, a ram movable by hydraulic means in said cylinder, movable means for receiving a formed product, and means automatically actuated upon the advance of said movable means through a predetermined distance, for interrupting the action of said expressing means.

14. In a machine for the formation of articles by extrusion, a cylinder for the reception of plastic material provided with a forming head, means for expressing said material through said forming head, said expressing means being hydraulically operated by a power fluid, movable means for receiving a formed product, and means automatically actuated upon the advance of said movable means through a predetermined distance for interrupting the action of said expressing means.

15. In a machine for the formation of articles by extrusion, the combination of a cylinder for the reception of plastic material provided with a forming head, means for expressing said material through said forming head, said expressing means being hydraulically operated, and means for automatically interrupting the action of said ex-

pressing means upon the extrusion of an article of predetermined length.

16. In a machine for the formation of articles by extrusion, the combination of a cylinder for the reception of plastic material, provided with a forming head, means for expressing said material through said forming head, and means for automatically interrupting the action of said expressing means upon the extrusion of an article of predetermined length.

17. In a machine for the formation of articles by extrusion, the combination of a cylinder for the reception of plastic material, provided with a forming head, a ram adapted to operate in said cylinder, hydraulic means for moving said ram including a pump, a tank, pipe means connecting said tank with said pump, and ram, and valve means positioned in said pipe means adapted to control the movement of said ram.

18. In a machine for the formation of articles by extrusion, the combination of a cylinder adapted to receive plastic material, said cylinder being provided with a forming head, a ram adapted to operate in said cylinder, hydraulic means for moving said ram including a pump, a tank, pipe means connecting said pump with said pipe and ram, valve means positioned in said pipe, means adapted to control movement of said ram, and means for automatically operating said valve and interrupting the action of said ram upon the extrusion of an article of predetermined length.

In testimony whereof, we have hereunto set our hands at Los Angeles, California, this 2nd day of November, 1927.

WILLIAM McCLINTOCK.
FRANK Y. PEARNE.
